CONVEYER AND GUIDE

Albert Broadmeyer, Norwalk, Conn.

Application November 2, 1945, Serial No. 626,312

13 Claims. (Cl. 271—49)

1

This invention relates to conveying mechanisms for paper or like sheets, and is concerned particularly with improvements in means for positioning sheets relative to a conveyor by urging them laterally against a guide rail as they are advanced by the conveyor.

In accordance with known practice, the present means for the purpose stated comprises, generally speaking, one or more rollers mounted for peripheral contact with the advancing sheets and having its axis or their axes of rotation inclined to the direction of advance of the sheets, whereby the sheets are urged laterally against a guide rail as they are advanced. Heretofore, such rollers usually have been disposed to have the sheets pass thereover and weight elements usually have been provided to rest upon the sheets to hold them engaged with the rollers. Moreover, the rollers usually have been driven by means other than the sheets themselves to accomplish their purpose.

Generally speaking, the object of the present invention is to provide inclined roller means for the purpose stated which are considerably simplified and more efficient than prior inclined roller means for the same purpose.

More particularly, special and important objects of the present invention are: to provide inclined roller means for the purpose stated which are readily adaptable to operate equally as well upon paper or other sheets of different weights and textures and which are not required to be driven by means other than the advancing sheets themselves to urge the sheets against a guide rail.

With the foregoing and other objects in view, which will become more fully apparent as the nature of the invention is better understood, the same consists in inclined roller means for the purpose stated embodying the novel features of construction, combination and arrangement of parts as will be hereinafter more fully described, illustrated in the accompanying drawings and defined in the appended claims.

In the accompanying drawings, wherein like characters of reference denote corresponding parts in the different views:

Fig. 1 is a top plan view of a sheet conveying mechanism embodying sheet positioning means constructed and arranged in accordance with the invention;

Fig. 2 is a side elevation of the mechanism shown in Fig. 1;

Fig. 3 is an enlarged top plan view of one of the sheet positioning inclined roller devices;

2

Fig. 4 is an enlarged side elevation of one of the sheet positioning inclined roller devices; and Fig. 5 is a transverse section.

Referring to the drawings in detail, A designates, generally, a portion of a sheet conveyor of a known type comprising a plurality of endless tapes 10 trained over a pair of rollers 11 and 12, and B designates, generally, a guide for the sheets located at one side of the conveyor A.

10 The tapes 10 and the rollers 11 and 12 are disposed substantially horizontally and one of the rollers may be driven in any suitable manner to cause the upper or active reaches of the tapes 10 to travel in the direction of the arrow *a* in Fig. 1.

While the sheet guide B may be of any suitable form, it preferably is in the form of a piece of angle iron substantially coextensive in length with the conveyor A and having one of its flanges 20 14 disposed vertically and its other flange 15 disposed horizontally and extending inwardly from the top of its flange 14 into overlying relationship to an outermost tape 10 of the conveyor A.

Underlying and supporting the upper or active reach of the said outermost tape 10 is a bar 16 which is substantially coextensive with the guide B and which may be mounted, for example, upon the vertical flange 14 of said guide.

The sheets *s* of paper or the like to be advanced by the conveyor A may be fed to the upper or active reaches of the tapes 10 in any suitable manner, and the purpose of the present invention is to provide improved means for urging the sheets laterally outward as they are advanced to cause their outer edges to engage the guide rail constituted by the vertical flange 14 of the guide B, whereby they will be properly positioned when they reach the discharge end of the conveyor to be fed to a printing or other mechanism which operates upon them.

The means for urging the sheets *s* laterally as they are advanced may comprise only a single device C located at any suitable point along the length of the conveyor A, or a plurality of devices C located at suitably spaced points along the length of said conveyor.

Preferably the said means comprises a plurality of the devices C and preferably said devices are duplicates of one another. Therefore a description of one will suffice for all.

Thus, any given device C comprises a block 17 resting upon the top flange 15 of the guide B and pivoted intermediate its ends to said top flange, as indicated at 18, for rotary adjustment 65 in a substantially horizontal plane.

At its end nearer the discharge end of the conveyor A the block 17 has suitably pivoted thereto, as indicated at 19, one end of an arm 20, whereby said arm is swingable in a vertical plane relative to said block and also is swingably adjustable in a horizontal plane in harmony with rotative adjustments of said block.

At its free end the arm 20 carries a suitable roller 21, while in the flange 15 of the guide B is an opening 22 through which said roller extends for peripheral contact at its bottom with the upper face of the marginal portion of a sheet s resting upon the conveyor tapes 10. The bar 16 supports the outermost tape 10 and the outer marginal portion of the sheet s against downward movement and the roller 21 overlies said bar and the said marginal portion of the sheet with which it is maintained engaged by its own weight and the weight of said arm. Thus, as the upper or active reaches of the conveyor tapes 10 are advanced in the direction of the arrow a and advance the sheet s resting thereon, the frictional contact between the sheet and the roller results in rotation of the roller in the direction of the arrow b in Fig. 4. The roller 21 has its axis of rotation disposed at an inward and forward inclination relative to the conveyor A. In other words, the roller itself is disposed in a vertical plane inclined forwardly and outwardly relative to the conveyor A. Consequently, as said roller is rotated by advance of the sheet s it tends constantly to urge the sheet laterally outward. It results, therefore, that as the sheet is advanced it is urged outwardly to bring its outer edge into engagement with the inner face of the vertical flange 14 of the guide B and to maintain such engagement, whereby, when it reaches the discharge end of the conveyor, it will be properly positioned to be fed to a printing or other mechanism for operating upon the same.

While any suitable means may be provided for rotatably adjusting the block 17 to secure a desired angular adjustment of the roller 21 relative to the conveyor A, one suitable and practical means for this purpose may consist, as shown, of a screw member 23 threaded through a post 24, swiveled to said block 17 and extending loosely through a bracket 25 fastened to the guide B. The screw member may have a shoulder 23' engaging the outer face of the bracket 25 and an expansion helical spring 26 may surround said screw member between said bracket to tend constantly to swing the rear end of the block 17 inwardly. Obviously, therefore, by rotatably adjusting said screw member, fine angular adjustments of the roller 21 may be obtained and will be maintained. In this connection it is a desirable and advantageous feature of the invention that the screw member 23 is exposed for ready and convenient adjustment at any time, which is of importance in securing just the required angular adjustment of the roller 21 to urge the sheet s against the guide rail 14 without imposing undesirable drag upon the sheet. To facilitate adjustment of the screw member 23, the same may be provided with a knurled head 27.

Although dependence may be placed solely in the weight of the arm 20 and the roller 21 to maintain pressure of said roller against the sheet s, adjustable means preferably is provided whereby the pressure of said roller against said sheet may be varied. This means may be of any suitable form and is illustrated in the drawings as

comprising a rod 28 carried by the arm 20 and extending in overlying relationship thereto and having a weight 29 slidably adjustable therewith. A set screw 30 may be carried by said weight for cooperation with said rod to maintain any desired adjustment of said weight. Obviously, by adjusting said weight along the rod 28 the pressure of the roller 21 against the sheet s may be varied, which is of importance in adapting the mechanism to operate most effectively upon sheets of different weights and textures. The rods 28 and the weights 29 are not shown in Fig. 1 in order to avoid confusion.

If a plurality of the devices C are provided at spaced intervals along the length of the conveyor, said devices obviously will act successively upon sheets advanced by the conveyor. The roller 21 preferably is supported by an anti-friction bearing whereby it is freely rotatable and its peripheral portion preferably is composed of rubber or other suitable friction material for firm engagement with the sheets s.

From the foregoing description considered in connection with the accompanying drawings it is believed that the construction and operation of the present mechanism will be clearly understood and its advantages appreciated. It is desired to point out, however, that while only a single specific structural embodiment of the invention has been illustrated and described, the same is readily capable of specifically different structural embodiments within its spirit and scope as defined in the appended claims.

I claim:

35. 1. In a sheet conveying mechanism, a sheet supporting and conveying member, a guide rail for supporting said member and to be engaged by an edge of a sheet supported by and being conveyed by said member, a roller mounted above the guide rail to rest upon and to be rotated by the sheet as the latter is advanced by the conveying member over the guide rail, and means mounting said roller for free downward movement into engagement with the sheet and for adjustment to different inclinations relative to the conveying member to cause it to urge the sheet laterally against said guide rail as it is rotated.
40. 2. In a sheet conveying mechanism, a sheet supporting and conveying member, means to support said member against downward movement, a guide rail to be engaged by a side edge of a sheet supported by and being advanced by said conveying member, and a roller mounted to gravitate into engagement with a sheet supported by said conveying member and to be rotated by the sheet as the latter is advanced, the downward movement of the roller being limited by the supporting means for the conveying element, and said roller being disposed at an inclination to the conveying member such that its rotation by the advancing sheet urges the sheet laterally into engagement with said guide rail.
45. 3. In a sheet conveying mechanism, a sheet supporting and conveying member, a guide rail to be engaged by an edge of a sheet supported by and being conveyed by said member, a block pivoted for rotative adjustments in a horizontal plane, an arm pivoted at one end to said block for vertical swinging movement relative thereto and for rotative adjustment in a horizontal plane therewith, a roller carried by the other end of said arm to gravitate into engagement with a sheet supported by said conveying member and to be rotated by the sheet as the latter is ad-

vanced, and means for rotatively adjusting said block to and holding it in a position to dispose said roller at an inclination to the conveying member to cause it to urge the sheet laterally into engagement with said guide rail as it is rotated by advance of the sheet.

4. A sheet conveying mechanism as set forth in claim 3 in which the block adjusting means comprises a fixed bracket, a screw member extending loosely through said bracket and having a shoulder engageable with the outer side thereof, a post swiveled to the block and having said screw member threaded therein, and an expansion spring interposed between said bracket and said post.

5. A sheet conveying mechanism as set forth in claim 3 in which a rod is carried by and overlies the arm, and in which a weight element is adjustable along said rod to vary the pressure of the roller upon the sheet.

6. In a sheet conveying mechanism, an endless sheet supporting and conveying tape including a lower reach and an upper or active reach, an angle member extending contiguously to said upper reach, said angle member including a horizontal flange overlying said upper reach and a vertical flange disposed at the outer side thereof, a supporting bar for said upper reach underlying the same and carried by said vertical flange, a block pivoted to said horizontal flange for rotative adjustments in a horizontal plane, an arm pivoted at one end to said block for vertical swinging movement relative thereto and for rotative adjustments therewith, a roller carried by the other end of said arm to gravitate into peripheral engagement with a sheet supported by said upper reach, and to be rotated by the sheet as the latter is advanced, said upper flange having an opening through which said roller may gravitate into engagement with the sheet, and means for rotatively adjusting said block to adjust said roller to an inclination relative to said upper reach to cause said roller to urge the sheet laterally outward against said vertical flange as it is rotated by advance of the sheet.

7. A sheet conveying mechanism as set forth in claim 6 including adjustable weight means carried by the arm to vary the pressure of the roller against the sheet.

8. A sheet conveying mechanism as set forth in claim 6 in which the means for rotatively adjusting the block comprises a screw member having a head exposed at the outer side of and above the angle member for free access at all times to effect the adjustments.

9. In a sheet conveying mechanism, a sheet supporting and conveying member composed of a plurality of spaced endless tapes disposed in parallel relation to each other, a guide rail for supporting one of the outermost of said tapes to prevent downward movement thereof and to be engaged by an edge of a sheet supported by and being conveyed by said conveying member, means mounted above the guide rail and the said one of the outermost tapes of the conveying element to rest upon and to be rotated by the sheet as the latter is advanced, and means mounting said first-named means for free downward movement into engagement with that portion of the sheet overlying the said tape supported by the guide rail and for adjustment to different inclinations relative to the effective path of movement of the conveying member to cause the same to urge the sheet laterally against said guide rail as it is rotated.

10. In a sheet conveying mechanism, a sheet

supporting and conveying member, a guide rail for supporting one of the outer edge portions of said member to prevent downward movement thereof and to be engaged by an edge of a sheet supported by and being conveyed by said member, antifriction means mounted above the guide rail and the said outer edge portion of the member to be supported thereby so as to rest upon and be actuated by the sheet as the latter is advanced, and means mounting said anti-friction means for free downward movement into engagement with that portion of the sheet overlying the portion of the member supported by the guide rail and for adjustment to different inclinations relative to the effective path of movement of the conveying member to cause said anti-friction means to urge the sheet laterally against said guide rail as said anti-friction means is actuated.

11. In a sheet conveying mechanism, a sheet supporting and conveying member, a guide rail to be engaged by an edge of a sheet supported by and being conveyed by said member, an element mounted for rotative adjustments in a horizontal plane, an arm movably connected to said element for vertical movement relative thereto and for rotative adjustment in a horizontal plane therewith, rotatable means carried by the other end of said arm to gravitate into engagement with a sheet supported by said conveying member and to be rotated by the sheet as the latter is advanced, and means for rotatively adjusting said element to and for holding the latter in a position to dispose said rotatable means at an inclination to the conveying member to cause the same to urge the sheet laterally into engagement with said guide rail as it is rotated by advance of the sheet.

12. In a sheet conveying mechanism, a sheet supporting and conveying member, a guide rail for supporting one of the outer edge portions of said member to prevent downward movement thereof and to be engaged by an edge of a sheet supported by and being conveyed by said member, an element mounted for rotative adjustments in a horizontal plane, an arm movably connected to said element for vertical movement relative thereto and for rotative adjustment in a horizontal plane therewith, rotatable means carried by the other end of said arm to gravitate into engagement with a sheet supported by said conveying member at a point above said outer edge portion of the conveying member which is supported by the guide rail and to be rotated by the sheet as the latter is advanced, and means for rotatively adjusting said element to and for holding the latter in a position to dispose said rotatable means at an inclination to the conveying member to cause the same to urge the sheet laterally into engagement with said guide rail as it is rotated by advance of the sheet.

13. In a sheet conveying mechanism, a sheet supporting and conveying member, a guide rail to be engaged by an edge of a sheet supported by and being conveyed by said member, means carried by the guide rail for supporting the adjacent portion of the active part of the conveying member, an element mounted for rotative adjustments in a horizontal plane, an arm movably connected to said element for vertical movement relative thereto and for rotative adjustment in a horizontal plane therewith, rotatable means carried by the other end of said arm above that portion of the conveying member sup-

ported by the supporting means carried by the guide rail so as to gravitate into engagement with a sheet supported by said conveying member, and to be rotated by the sheet as the latter is advanced, and means for rotatively adjusting said element to and for holding the latter in a position to dispose said rotatable means at an inclination to the conveying member to cause the same to urge the sheet laterally into engagement with said guide rail as it is rotated by advance of the sheet.
